UNITED STATES PATENT OFFICE

FRED HIRSH, OF NEW YORK, N. Y., ASSIGNOR TO ADJUSTA COMPANY, A CORPORATION OF NEW YORK

DESIGN FOR AN APPAREL CLASP

Application filed October 15, 1931. Serial No. 41,398. Term of patent 3½ years.

To all whom it may concern:

Be it known that I, FRED HIRSH, a citizen of the United States, residing in the city of New York, in the county of New York and State of New York, have invented a new, original, and ornamental Design for Apparel Clasp, of which the following is a specification, reference being had to the accompanying drawings, forming part thereof.

Figure 1 is a front perspective view of an

apparel clasp, showing my new design; and Figure 2 is a side elevation of the same.

The design relates particularly to the front or face of the clasp, which front is a semi-circular double wire extending from the apex to the shortest side of a triangular base.

I claim:

The ornamental design for an apparel clasp as shown and described.

FRED HIRSH.
